INSTANTANEOUS BACKSTOP ELEVATING APPARATUS

Ernest C. Webb, Bay Village, Ohio, assignor to Lakewood Manufacturing Company, Westlake, Ohio, a corporation of Ohio

Filed Feb. 7, 1963, Ser. No. 256,890

3 Claims. (Cl. 273—49)

This invention relates to apparatus for elevating a backstop, and more particularly to apparatus responsive to the impact of a bowling ball with the backstop for instantaneously elevating the backstop.

Most modern automatic pin-spotting equipment includes structure for suspending a backstop above the pit floor of a bowling alley. Incorporated in this structure is automatic equipment for firstly elevating the backstop to permit the passage of bowling balls to the ball return equipment and secondly for lowering the backstop to prevent the direct passage of bowling balls which have been delivered by a player.

The automatic equipment for elevating and lowering the backstop usually includes a cam arrangement which is timed in with the pin-spotting cycle of the pin-spotter equipment. Hence, it is normal in this arrangement to have a delay in the elevation of the backstop, and hence, a delay in the return of the bowling ball to the player. This delay normally is in the range of 1 to 4 seconds.

It is a primary object of this invention to provide a backstop elevating apparatus which will instantaneously elevate the backstop thereby decreasing the time involved in returning the bowling ball to the player.

It is another object of this invention to provide backstop elevating apparatus which is responsive to the impact of a bowling ball with the backstop for instantaneously elevating the backstop.

A further object of this invention is to provide backstop elevating apparatus which may be used in existing automatic pin-spotting equipment.

Another object of this invention is to provide backstop elevating apparatus which is relatively inexpensive to manufacture and operate.

Still another object of this invention is to provide backstop elevating apparatus which is reliable in operation.

These and other objects and advantages of the present invention will become apparent from the following detailed description by reference to the accompanying drawings, and in which:

FIGURE 1 is an elevation view of the present backstop elevating apparatus, as used in the pit area of the bowling alley, with the backstop lowered into a ball deflecting position;

FIGURE 2 is an elevation view, similar to FIG. 1, of the present backstop elevating apparatus but with the backstop in a raised position; and

FIGURE 3 is a schematic illustration of the control circuit of the present backstop elevating apparatus.

Referring to FIG. 1, a pit area 10 is shown which includes a pin deck 12, a pit floor 14, a backstop 16, a curtain 18, a kickback 20 and kickback plate 22.

In this illustration, the pit floor 14 is of the vibratory type and is sloped downwardly from the pin deck 12 toward the rear of the pit area 10. The pit floor 14, by virtue of its slope and vibratory motion, serves to convey the pins under the backstop 16 to the automatic pin-setting equipment and when it is raised as in FIG. 2, to convey bowling balls to the ball return equipment (not shown), respectively. The kickback 20 and the kickback plate 22 serve among other things to deflect flying

tenpins. The backstop 16 and the curtain 18 serve to deflect flying tenpins onto the pit floor 14.

The backstop 16 also serves the important function of absorbing the impact of a bowling ball 24 and thereby stop its forward progress. As can be seen in FIG. 1, the backstop 16 includes support arms 26 (only one shown) which extend upwardly therefrom. The upper end of each support arm 26 extends through and is supported by a guide conduit 28 which permits the backstop 16 to be elevated vertically with respect to the pit floor 14. Although a specific means has been illustrated by which the backstop 16 may be supported in vertically adjustable relation with the pit floor 14, it should be evident that any suitable means may be employed.

A backstop elevating apparatus 30 is shown comprising elevating means 32 and switch means 34.

The elevating means 32 preferably comprises a pneumatically operated cylinder 36 pivotally supported at its upper end by a hinge connection 38 which is secured to a suitable support structure. The cylinder 36 includes a shaft 40 having a first end 42 extending into the cylinder 36 and connected to a piston 44; and a second end 46 extending downwardly therefrom and connected to an angle member 48 which is rigidly secured to the backstop 16. The second end 46 of the shaft 40 preferably is connected to the angle member 48 in a manner which will permit the backstop 16 to be elevated by the existing backstop elevating mechanism of the automatic pin-spotting equipment independent of the elevating means 32. This is accomplished, in the present apparatus, by providing a nut on the second end 46 which is adapted to be engaged by the angle member 48 only from above. Notice, then, that the angle member 48 is free for vertical longitudinal movement with respect to the shaft 40. Hence, the present backstop elevating apparatus may be used in existing automatic pin-spotting equipment.

A conduit 50, preferably of the flexible type, is connected to the cylinder 36 at a point below the piston 44. The conduit 50 serves to introduce and exhaust a working fluid, preferably comprising compressed air, from the interior of the cylinder 36 in a manner which will be described later in conjunction with FIG. 3.

The switch means 34 preferably comprises a suitable electrical switch 52 rigidly supported on the structure of the pit area 10 and a switch operating means or probe 54 extending therefrom. The probe 54 comprises a rod slidably supported in a tube 56 which is rigidly secured to the structure of the pit area 10. The probe 54 preferably includes an enlarged end portion 58 engaged with a slide plate 60 secured to the back of the backstop 16. The slide plate 60 provides a smooth surface on which the enlarged end portion 58 will slide when the backstop 16 is elevated (see FIG. 2).

The pneumatic and electrical control circuits of the backstop elevating means 32 are schematically illustrated in FIG. 3.

The pneumatic control circuit includes the conduit 50 extending from the cylinder 36 to one outlet of a two-way valve 62; a supply conduit 64 extending from a second outlet of the two-way valve 62 to a source of working fluid schematically represented at 66; and a vent conduit 68 extending from a third outlet of the two-way valve 62. The two-way valve 62 has a first position wherein the working fluid may be introduced into the cylinder 36 by way of conduits 50, 64; and a second position wherein the supply conduit 64 is sealed off and wherein the working fluid in the cylinder 36 may be vented to the atmosphere by way of conduits 50, 68.

The positions of the two-way valve 62, that is, supplying or venting, are controlled by means of a solenoid 70 which comprises a coil 72 and a core 74.

The core 74 preferably is spring-loaded in a direction which maintains the two-way valve 62 in its second or venting position, i.e., wherein conduit 50 communicates with the vent conduit 68.

The coil 72 preferably is connected to the switch 52 through a first pair of contacts 76. The contacts 76 provide a direct connection between the solenoid 70 and the switch 52 and consequently the closing of the switch 52 will instantaneously energize the solenoid 70 to raise the backstop 16.

It is sometimes desirable to have a very slight delay between the closing of the switch 52 and the energization of the solenoid 70 for raising the backstop 16. Alternatively then, the coil 72 may be connected to the switch 52 through a second pair of contacts 78 which connect a time delay circuit 80 into the control circuit. The time delay circuit 80 provides this slight delay. The selection of which pair of contacts, 76 or 78, is to be used is afforded by the manually operated pushbutton switch 82.

When an instantaneous elevation of the backstop 16 is desired, the operation of the present backstop elevating apparatus is as follows. The manually operated pushbutton switch 82 is positioned so that contacts 76 are used to directly connect the solenoid 70 to the switch 52. Thus, when a ball 24', illustrated in phantom outline in FIG. 1, hits the backstop 16, the switch 52 will be closed to instantaneously energize the solenoid 70 whereupon the working fluid is communicated to the operating cylinder 36 to raise the backstop 16. Meanwhile, the ball 24' will drop to the position indicated at 24. When the backstop 16 is raised, as shown in FIG. 2, the slope and vibratory motion of the pit floor 14 will convey the ball 24 under the backstop 16 to the ball return mechanism.

When a slight delay is required in the elevation of the backstop 16, the manually operated pushbutton switch 82 is depressed to connect the contacts 78 which interpose the time delay circuit 80 into the control circuit. Thus, when the ball 24' hits the backstop 16, the switch 52 will be closed. However, since the time delay circuit 80 is operative in this circuit, a very slight delay will occur before the energization of the solenoid 70. When the solenoid 70 is energized, the working fluid is communicated to the operating cylinder 36 to raise the backstop 16. Meanwhile, the ball 24' will drop to the position indicated at 24 and the slight delay provided by the time delay circuit 80 will permit the ball 24 to be engaged with the backstop 16 preparatory to its passing thereunder. When the backstop 16 is raised, as shown in FIG. 2, the mechanized pit floor 14 will convey the ball 24 under the backstop 16 to the ball return mechanism.

Although the invention has been shown in connection with a certain specific embodiment, it will be readily apparent to those skilled in the art that various changes in form and arrangement of parts may be made to suit requirements without departing from the spirit and scope of the invention.

I claim as my invention:

1. In apparatus for momentarily elevating a backstop suspended above the pit floor of a bowling alley, the combination comprising:

a backstop suspended above a pit floor in vertically adjustable relation therewith;

elevating means for rapidly elevating said backstop

above said pit floor, said elevating means comprising a fluid operated cylinder pivotally supported at one end to extrinsic support structure and a piston shaft extending from said cylinder and connected to said backstop;

switch means actuatable by the impact of a bowling ball with said backstop; and

circuit means responsive to the actuation of said switch means for energizing said elevating means whereby said backstop is elevated immediately to permit said bowling ball to pass.

2. In apparatus for momentarily elevating a backstop suspended above the pit floor of a bowling alley, the combination comprising:

a backstop suspended above a pit floor in vertically adjustable relation therewith;

elevating means for rapidly elevating said backstop above said pit floor, comprising a fluid operated cylinder means pivotally supported at one end to extrinsic support structure and piston shaft extending therefrom and connected to said backstop;

switch means actuatable by the impact of a bowling ball with said backstop, said switch means including a switch operating probe connecting said backstop directly with said switch means; and

circuit means responsive to the actuation of said switch means for energizing said elevating means whereby said backstop is elevated immediately to permit said bowling ball to pass.

3. In apparatus for momentarily elevating a backstop suspended above the pit floor of a bowling alley, the combination comprising:

a backstop suspended above a pit floor in vertically adjustable relation therewith;

elevating means for rapidly elevating said backstop above said pit floor, comprising a fluid operated cylinder pivotally supported at one end to extrinsic support structure and a piston shaft extending therefrom and connected to said backstop;

a source of pressurized fluid;

conduit means connecting said source of pressurized fluid with said cylinder;

unitary valve means in said conduit means for communicating said fluid to said cylinder means and for venting said fluid from said cylinder means, said unitary valve means including valve operating means;

switch means actuatable by the impact of a bowling ball with said backstop; and

circuit means responsive to the actuation of said switch means for energizing said valve operating means to communicate said fluid to said elevating means whereby said backstop is elevated immediately to permit said bowling ball to pass.
